UNITED STATES PATENT OFFICE

121,598

DESIGN FOR A ROASTING RACK

George V. Post, Los Angeles, Calif.

Application April 8, 1940, Serial No. 91,537

Term of patent 3½ years

To all whom it may concern:

Be it known that I, George V. Post, a citizen of the United States of America, residing in Los Angeles, in the county of Los Angeles, State of California, have invented a new, original, and ornamental Design for A Roasting Rack, of which the following is a specification, reference being had to the accompanying drawing, forming a part thereof.

In the drawing the figure is a view in perspective of the roasting rack showing my design.

I claim:

The ornamental design for a roasting rack, as shown.

GEORGE V. POST.
